UNITED STATES PATENT OFFICE.

HENRY A. CHRISTY, OF JACKSON, MICHIGAN.

DESIGN FOR A SADDLE-SEAT FOR BICYCLES.

SPECIFICATION forming part of Design No. 27,185, dated June 8, 1897.

Application filed April 17, 1897. Serial No. 632,677. Term of patent 7 years.

To all whom it may concern:

Be it known that I, HENRY A. CHRISTY, a citizen of the United States, residing at Jackson, in the county of Jackson and State of Michigan, have invented and produced a new and original Design for Saddle-Seats for Bicycles; and I do hereby declare the following to be a full, clear, and exact description of the same.

This invention relates to saddle-seats, but more particularly to designs for the seats of saddles for bicycles, velocipedes, and other wheeled vehicles adapted to be propelled by a person sitting on the seat mounted thereon.

The design consists, essentially, of the seat portion of the saddle, having a main body portion similar to the body portion of a palm-leaf fan, with a recess at either side thereof and a shortened-up or truncated horn forming a continuation of a centrally-disposed raised portion or bar extending longitudinally of the seat between the aforesaid recesses, said centrally-disposed raised portion having a recess or depression extending longitudinally thereof from a point between said sunken portions to near the front edge or end of the horn.

In the accompanying drawings, which form a part of this specification and in which similar letters of reference are used to denote similar parts in different views, Figure 1 represents a plan or top view of a saddle-seat constructed in accordance with my design. Fig. 2 is a transverse section taken on the line II II of Fig. 1, and Fig. 3 is an inverted plan or bottom view of the seat shown in Fig. 1.

In the drawings, A denotes the main body portion of the saddle-seat, and B the shortened-up or truncated horn thereof, which together are approximately of the shape or configuration of a palm-leaf fan with a stub handle or stem, though the rear of the seat is more gently curved and its sides convex, said horn in the design for the seat corresponding with the stem of the leaf. The body portion A is somewhat wider than the ordinary saddle-seat, and is formed with a centrally-disposed raised portion or bar *a* and a recess or sunken portion *a'* at either side thereof, said bar *a*

being continued or extending sufficiently forward of the seat portion proper to form a shortened-up or truncated horn, as at B. The horn B is provided on its upper surface or top with a depression or recess *b*, forming a continuation of a recess *a²* in the upper surface of the bar *a*.

The rear portion or edge and sides of the seat may be curved, as shown, the latter terminating in such manner as to form, with the continuation of the centrally-disposed bar *a*, the horn B. On the opposite side or bottom of the seat appears a smooth or approximately flat substantially segment-shaped surface *a³* at either side of a depression or recess *a⁴*, which extends longitudinally of the seat from the rear edge thereof to near the end of the horn B, said surfaces *a³* being the bottoms of the recesses or depressions *a'* on the opposite side. Extending longitudinally of the recess *a⁴* and horn B on the under side of the seat is a rib or raised portion *a⁵*, which forms the bottom of the recess *a² b* on the upper or opposite side, and a depression or groove *a⁶* extends around the marginal portion or edge of the seat portion A from the horn B to the rear of the recess *a⁴* at each side.

It will thus be seen that the leading features of my design reside in the transversely-elongated approximately fan-shaped configuration of the seat having a depression or recess in the body portion thereof at each side of its longitudinal center, a stub or truncated horn forming a continuation of the curved sides and centrally-disposed bar extending longitudinally of the body of the seat, a pendent flange or edge overhanging said sides and horn, and a recess extending longitudinally of said centrally-disposed bar and horn.

What I claim is—

The design for a saddle-seat substantially as shown and described.

In testimony whereof I affix my signature in the presence of two witnesses.

HENRY A. CHRISTY.

Witnesses:

W. S. COBB,
THOMAS A. WILSON.
